UNITED STATES PATENT OFFICE.

SOREN F. PETERSEN, OF CHICAGO, ILLINOIS.

MOP.

1,342,182.

Specification of Letters Patent. Patented June 1, 1920.

Application filed November 10, 1919. Serial No. 337,015.

To all whom it may concern:

Be it known that I, SOREN F. PETERSEN, a citizen of the United States, and a resident of Chicago, in the county of Cook and State 5 of Illinois, have invented certain new and useful Improvements in Mops, of which the following is a specification, reference being had to the accompanying drawings.

My invention relates to mops and it has 10 for its principal object the provision of a new and improved form and arrangement of parts by which a wringing device is incorporated in the structure of the mop. It is another object of my invention to provide 15 a mop of this type so arranged and organized that the added feature may be employed without affecting the efficiency of the mop for cleaning purposes and that the device as a whole may be neat and light and may be 20 capable of being produced and assembled readily and cheaply. It is another object of my invention to improve mops and wringing devices in sundry details herein-after pointed out. The preferred means by 25 which I have accomplished my several objects are illustrated in the drawings and are hereinafter specifically described. That which I believe to be new and desire to 30 cover by Letters Patent is set forth in the claims.

In the drawings,—

Figure 1 is a face view of a mop embodying my improvements, both the handle and the mopping member being broken away 35 close to the head of the mop.

Fig. 2 is a side view of the parts shown in Fig. 1.

Fig. 3 is a partial face view as seen from the left in Fig. 2 but with the parts in 40 changed position in a wringing operation.

Fig. 4 is a central vertical section, taken substantially on line 4—4 of Fig. 2.

Fig. 5 is a transverse vertical section, being taken substantially on line 5—5 of 45 Fig. 3.

Referring to the several figures of the drawings in which corresponding parts are indicated by the same reference characters, 50 10 indicates a mop handle having arms 11 and 12 secured thereon and extending outwardly therefrom, between the turned ends of which arms is revolvably mounted the head of the mop as hereinafter described.

As is best shown in Figs. 4 and 5, the head 55 of the mop is in the form of a clamping device comprising a bar 13 and a trough-

shaped bar 14 secured at its ends to the bar 13 by means of bolts 15. The bar 13 extends through suitable openings in the lower turned ends of the arms 11 and 12, which 60 are held against a spreading movement longitudinally of the bar 13 by means of a second bar 16 which is secured in position by the bolts 15, the bar 16 having its outer ends turned down on the outer faces of the arms 65 11 and 12 as shown in said Fig. 4. As is best shown in Fig. 5 the mopping member 17, which in the construction shown is in the form of a plurality of strands, is secured firmly between the bars 13 and 16 on one 70 side and the trough-shaped bar 14 on the other side, the trough-shaped bar 14 serving to surround or inclose the strands which are looped about the bars 13 and 16 whereby the strands are clamped securely against 75 withdrawal. At the same time when it is desired to remove the strands, this can be accomplished readily by the removal of the bolts 15. Washers 18 are employed about the bars 13 and 16 and within the trough-shaped bar 14 serving to keep the strands out of the bearing of the head in the arms 80 11 and 12. These washers also act as rollers, serving to protect the floor.

The bar 13 is provided with a crank handle 19 at one end, in the construction shown this handle being formed integrally with the bar. By the use of the handle 19, the head is adapted to be rotated between the arms 11 and 12 serving to roll the mopping member about the head as is shown in Figs. 3 and 5, the mopping member being adapted to be rotated with the head as long as it may be desired. Means is provided for holding the head against rotation comprising a slide 90 block 20, mounted upon the arm 11 and carrying a stop device 21 substantially in the form of a yoke having prongs adapted to extend on opposite sides of the handle 19 for holding the handle against turning. 100

The means for wringing the water from the mopping member comprises a bar 22 spaced a short distance from the head of the mopping member as is shown in Fig. 1 whereby the mopping member, as it is 105 brought into contact with said bar in the rotation of the mopping member about the axis of the head of the mop, is pressed upon by the bar. In the construction shown, the bar 22 is movably mounted with respect to 110 the head of the mop, and yielding means is employed for holding the bar yieldingly in

position for the wringing operation. To this end the bar 22 is provided with clips at its ends surrounding the turned end portions of the arms 11 and 12 and slidable along said arms, the clips in the construction shown being provided by the metal strip 23 secured upon one face of the bar 22 and having its ends turned about the ends of the bar 22 so as to embrace the arms 10 11 and 12. The resilient means for holding the bar 22 yieldingly in position is in the form of a spring 24 connected at one end to the lower end of the handle 10 and at the other end to an arm 25 extending upward along the handle from the bar 22. In the construction shown the arm 25 is in the form of a heavy wire having a loop 26 extending around the handle 10 and slidable longitudinally thereof, the ends of the wire being secured to the bar 22 by engagement with suitable sockets in the bar underneath the metallic strip 23. A collar 27 fixed upon the handle 10 by means of a screw 28 serves as a stop for limiting the downward movement of the bar 22.

By the use of my construction as above described, the water is adapted to be pressed out of the mopping member very quickly and easily, ordinarily a single revolution of the handle being sufficient to secure the desired wringing effect, after which a slight manipulation of the handle back and forth serves to straighten out the strands.

By reason of using a wide bar 14 about which the strands are wound in the wringing operation, the operator is enabled much more readily to throw off the strands after such wringing operation.

What I claim as my invention and desire to secure by Letters Patent, is—

1. A mop comprising a bar rotatable about a longitudinal axis, a mopping member secured upon said bar and rotatable therewith, and a second bar non-rotatively mounted in spaced relation to said first-named bar adapted to press against said mopping member for wringing the water therefrom as said mopping member is rotated with said first-named bar.

2. A mop comprising a handle, oppositely-disposed arms secured on the lower end portion of said handle, a bar rotatably mounted in suitable openings in said arms, a mopping member secured upon said bar and rotatable therewith, a second bar slidably mounted on said arms adjacent to said first-named bar, an arm mounted on said second bar extending along said handle, a collar on said handle serving to limit the movement of the arm mounted on said second bar for holding said bar at a distance from the first-named bar, and a spring connected between said handle and the arm on said second bar adapted to draw said second bar yieldingly toward said first-named bar so as to press upon said mopping member for wringing the water therefrom as said mopping member is rotated about said first-named bar.

3. A mop comprising a handle, oppositely-disposed arms secured on the lower end portion of said handle, a bar rotatably mounted in suitable openings in said arms, a second bar secured to said first-named bar and having its ends turned down on the outer faces of said arms, a mopping member secured on said bar, and means for rotating said bar and said mopping member.

4. A mop comprising a rotatably-mounted bar, a mopping member looped over said bar, a trough-shaped bar secured about said first-named bar and revolvable about the axis thereof, said trough-shaped bar extending at its sides substantially opposite said first-named bar and serving to clamp the mopping member thereon, means for rotating said first-named bar about its longitudinal axis serving to wind the mopping member about said bars, and a third bar adapted to press against the mopping member for wringing the water therefrom as said mopping member is carried around by said first-named two bars, said second bar serving substantially to space the end portions of the mopping member from the looped portion thereof when wound about said first-named bar for assisting in clearing the mopping member after a wringing operation.

SOREN F. PETERSEN.
